UNITED STATES PATENT OFFICE.

WALLACE H. CAMP, OF WATERBURY, CONNECTICUT, ASSIGNOR OF ONE-HALF TO BUSHROD H. CAMP, OF BOSTON, MASSACHUSETTS.

LOCK FOR POST-OFFICE BOXES.

SPECIFICATION forming part of Letters Patent No. 280,718, dated July 3, 1883.
Application filed November 7, 1882. (No model.)

To all whom it may concern:

Be it known that I, WALLACE H. CAMP, a citizen of the United States of America, residing at Waterbury, in the county of New Haven and State of Connecticut, have invented certain new and useful Improvements in Locks for Post-Office Letter-Boxes; and I do hereby declare the following to be a full, clear, and exact description of the invention, such as will 10 enable others skilled in the art to which it app pertains to make and use the same, reference being had to the accompanying drawings, and to letters or figures of reference marked thereon, which form a part of this specification, and 15 in which—

Figure 1 is a front view of a box with the door closed. Fig. 2 is a view with the door open, showing the inside of the door. Fig. 3 shows an end view of the door half way open. 20 Fig. 4 is a top plan view of Fig. 3.

My invention relates to certain improvements in locks for post-office letter-boxes, and has for its object to provide a lock for a letter-box which will be self-locking upon closing the 25 door, can be cheaply constructed, and by the use of which security and certainty of action are obtained; and it consists in certain novel construction and arrangement of parts, which I will now proceed to describe.

Referring to the drawings, A represents the 30 frame of the box; B, the door hinged to said frame; C, the frame of the door, the top of said frame extending down any suitable distance—say about one-fifth of the length of the 35 door—and having a lock attached in any suitable manner to the inner side of said top portion of the frame. D is the key-hole.

Extending across beneath the lock and around the remainder of the door-frame is the 40 inwardly-projecting flange *cccc*, within which, by means of pressure-springs M N, is held a glass plate. The pressure-springs M N are secured at each end in any suitable manner to the flange *cccc*, and are so curved or otherwise formed as to bear upon said glass plate 45 and afford it the necessary elastic pressure to prevent fracture or rattling when the door is suddenly or violently closed.

E is the lock, and may be of any suitable 50 construction. A spring-lock is preferably used.

F is a rod or lever working in bearings *a a'*, attached to the frame of the door, said rod having on one end below the bearing *a a'* a bolt or

catch, G, which engages with the inside of the 55 frame of the box, and serves to lock the door when shut, the rod or lever F being bent at right angles just above the bearing *a'* and again bent upward at the point *b*. Any suitable spring is applied to the rod F, the action of 60 which keeps the catching or locking end G thrown out from the door in a locking position.

In the drawings the spring H is coiled around the rod between the bearings *a* and *a'*, one end of which presses against the door-frame just 65 above the bearing *a*, and the other end pressing down on the horizontal portion of the rod F, thus keeping the end G in a position to lock the door when shut.

L is the slide of the lock, and has an inclined edge, *l*. Said slide, when drawn back by turning the key, engages with the upper portion of the rod F, forcing it out from the case of the lock, and thus withdrawing the locking or catch end G from contact with the inside of the frame of the box, and thereby unlocking the door. The key being released, the slide of the lock springs forward and the spring throws the rod F into its normal or locking position. The bolt G is so arranged as to present an inclined surface to the box-frame when 70 the door is being shut and the rod is in its normal position, and by pressing the door in, said 75 bolt is forced back and slides past the inside edge of the box-frame until the door is shut, 80 when the spring forces the bolt out against the inside of the box-frame and locks the door.

As a modification of my invention the lock may be placed at the bottom of the door and the lever or bent rod extend up instead of 85 down, and the bearings for the rod or lever may be constructed as part of the lock-case; or the catch or bolt may be located between the bearings and the lock-slide, so constructed 90 as to work directly on the catch or bolt.

Having thus fully described my invention, 95 I claim—

In a post-office box, the lock E, provided with a slide, L, having the inclined edge *l*, in combination with the bent rod F, working in 100 bearings *a a'*, having the bolt or catch G on one end, and the spring H, substantially as and for the purpose shown and described.

In testimony whereof I affix my signature in presence of two witnesses.
